(57) **CLAIM**

The ornamental design for a frame assembly for a paint bucket insert, as shown and described.

DESCRIPTION

FIG. 1 is an upper, perspective view of the frame assembly for a paint bucket insert and a wire mesh paint containment area surrounded by the frame assembly being shown in phantom;

FIG. 2 is a front elevational view of the frame assembly of FIG. 1;

FIG. 3 is a side elevational view of the frame assembly of FIG. 1;

FIG. 4 is a top plan view of the frame assembly of FIG. 1; and,

FIG. 5 is a bottom plan view of the frame assembly of FIG. 1.

The broken line showing of wire mesh in FIG. 1 is included for the purpose of illustrating and forms no part of the claimed design.
